(57) **CLAIM**

The ornamental design for a mounting platform for parallel connected solar cells, as shown and described.

DESCRIPTION

FIG. 1 is a top perspective view of a mounting platform for parallel connected solar cells showing my new design; FIG. 2 is an enlarged partial view thereof, taken from FIG. 1;

FIG. 3 is a top plan view thereof;

FIG. 4 is a bottom plan view thereof;

FIG. 5 is a front side elevation view thereof;

FIG. 6 is a rear side elevation view thereof;

FIG. 7 is a left side elevation view thereof; and,

FIG. 8 is a right side elevation view thereof.

The mounting platform for parallel connected solar cells is shown with a symbolic break in its length. The appearance of any portion of the article between the break lines forms no part of the claimed design.
